UNITED STATES PATENT OFFICE.

THOMAS F. LITTLE, OF CHICAGO, ILLINOIS.

ACETYLENE-GAS GENERATOR.

No. 874,970.

Specification of Letters Patent.

Patented Dec. 31, 1907.

Application filed September 7, 1907. Serial No. 391,796.

To all whom it may concern:

Be it known that I, THOMAS F. LITTLE, a citizen of the United States, residing at Chicago, in the county of Cook and State of Illinois, have invented certain new and useful Improvements in Acetylene-Gas Generators; and I do hereby declare the following to be a full, clear, and exact description of the invention, such as will enable others skilled in the art to which it appertains to make and use the same.

This invention relates to a novel construction in an acetylene gas generator, the object being to provide a device of this character which is very simple and durable in construction, and safe and efficient in operation, and consists in the features of construction and combinations of parts hereinafter fully described and claimed.

20 In the accompanying drawings illustrating this invention: Figure—1—is a plan section of a generator constructed in accordance with my invention. Fig. —2—is a central vertical longitudinal section of the same on the line 2—2 of Fig. —1—. Fig. —3—is a fragmentary detail view in elevation of the lower end of a blow-off passage employed.

My said invention has for its particular object, to provide an acetylene gas generator 30 which may be made in any desired size and for any desired capacity from a small portable apparatus suitable for all purposes for which portable illuminating apparatus is adapted, to generators of large capacity for 35 the illumination of large buildings, or groups of buildings.

The invention resides more particularly in the details of construction whereby important advantages over existing apparatus of 40 this character are gained, as will be pointed out in the following specification.

My said apparatus comprises the casing A of any suitable shape having a false bottom B below which is a chamber C. The upper 45 portion of said casing is provided with a central cylindrical compartment D open at its upper end, and connected at said end with a surrounding horizontal partition wall E disposed below the upper wall F of said casing. The latter is provided with a central opening concentric with and of considerably larger diameter than the said compartment D. In the space surrounding the cylindrical wall of said compartment D, there 55 are disposed two vertical partition walls G dividing said space into two compartments

H and I, the larger compartment H constituting the water reservoir and communicating at its upper end with the screw-capped tube J and at its lower end with the compartment D 60 through a plurality of openings K. The compartment I is filled with a fibrous material such as hair and communicates at its lower end with the compartment C through the opening L and at its upper end with the 65 gas outlet tube M.

A stand-pipe N establishes communication between the upper ends of the chambers C and D, the latter receiving the carbid bucket O having a concavo-convex bottom P and supported on legs Q, said bucket being of smaller diameter than said compartment and providing an annular space R between the wall thereof and said bucket in which said stand-pipe N is disposed. Said carbid 70 bucket is provided between its ends with a bead S indicating the maximum level of the carbid to be contained, and above said bead are one or more perforations T through which water is admitted to said bucket, the admitted water dripping upon the apex of the inverted V-shaped trough U secured to the inner face of the wall of said bucket and being thereby divided and caused to drip upon the carbid at two points from each perforation, 75 two of which disposed at diametrically opposite points are preferably provided. Entering said compartment D is a cylinder V open at its lower end and having a hollow tapered cap W communicating with the lower end of 80 said cylinder through the pipe or passage X provided in its lower end with an inverted V-shaped recess. At a diametrically opposite point said cap W communicates with a vent Y. Pivotaly mounted on the upper 85 wall F, are a plurality of latches Z which are adapted to engage the edge portions of the upper wall of said cap W to prevent the same from rising if desired. The said cylinder V constitutes the gasometer and receives the 90 stand-pipe N.

The operation of my generator is as follows: The cylinder V and carbid bucket O are removed, and the latter filled with carbid to the desired level. Said bucket and cylinder are then replaced and water is then introduced into the compartment H to fill the same about three quarters full. The gas outlet tube M being connected with the service pipes, the outlets from which are closed, the 100 water entering chamber D and flowing underneath the lower end of the cylinder V into

the annular space between the latter and the carbid bucket, cannot rise, in said space beyond the upper end of the V-shaped recess in the pipe X and, therefore, cannot reach 5 the perforations T. As soon, however, as an outlet in the service pipes is opened, the water will rise in said last named annular space, the displaced air passing through the stand-pipe N into compartment C and thence 10 through the purifier chamber I into the service pipes. As the water reaches said perforations T and flows through the latter upon the carbid, the gas generated will create pressure in the carbid bucket O and cylinder 15 V and force the level of the water down, the generated gas following the course of the displaced air as previously described. As the generated gas is gradually consumed, the water level rises, gas is again generated, and 20 this operation repeats so long as an outlet for the gas is open.

If, for example, a number of outlets have been continuously supplied by the generator for a considerable period and all of said outlets 25 are suddenly closed, the water held by the residue of consumed carbid will cause generation of gas to continue for some time and such gas having no outlet gradually forces the water level in the cylinder V to 30 recede until it falls below the upper end of the V-shaped recess in the pipe X through which the gas then passes into the said cap W and thence through the vent Y. This action also occurs in the event that at any time 35 an excess of water finds its way to the carbid and causes excessive generation. Some water is usually carried into the cap W by the carbid, but the escape of the latter through the vent Y is prevented by the relative positions 40 of said vent and said pipe X.

I prefer to lock the cylinder V in its lower most position by means of said latches Z but this is not essential as said cylinder may be left loose and allowed to rise and fall, thus 45 acting as a gasometer in an obvious manner.

To drain the water from the apparatus, I provide a drain pipe D¹ communicating with the lower end of the cylinder D, said drain pipe being maintained sealed by means of a 50 cap in a well known manner. The space between the walls E and F also serves to receive any water which may be thrown up through the annular space surrounding the cylinder V by reason of any excess of gas 55 generated suddenly, such water being prevented from leaving the apparatus by its deflection due to striking the tapered wall of the cap W.

The compartment C may be partly filled 60 with water through the stand-pipe N, such water serving to cool the gas passing through said compartment.

My said generator is very compact, and 65 operates very efficiently besides being safe and economical.

I claim as my invention:

1. An acetylene gas generator comprising a casing having a central compartment open at its upper end, a chamber in lower end communicating with the upper end of said central compartment through a stand pipe, a water chamber partly surrounding said central compartment and communicating at its lower end with the lower end of the latter, a purifier chamber communicating with said lower compartment and with the service pipes, a horizontal partition wall in said casing closing the upper end of the water chamber and the purifier chamber, a carbid bucket open at its upper end disposed in said central compartment, a cylinder open at its lower end entering said central compartment and receiving said carbid bucket and said stand pipe, a chamber above said cylinder communicating with the lower end of the latter, and a vent communicating with said chamber.

2. An acetylene gas generator comprising a casing having a central compartment open at its upper end, a chamber in lower end communicating with the upper end of said central compartment through a stand pipe, a water chamber partly surrounding said central compartment and communicating at its lower end with the lower end of the latter, a purifier chamber communicating with said lower compartment and with the service pipes, a horizontal partition wall in said casing, closing the upper end of the water chamber and the purifier chamber, a carbid bucket open at its upper end disposed in said central compartment, a cylinder open at its lower end entering said central compartment and receiving said carbid bucket and said stand pipe, a chamber above said cylinder communicating with the lower end of the latter, and a vent communicating with said chamber at a point substantially diametrically opposite the point of communication of said chamber with the said lower end of said cylinder.

3. An acetylene gas generator comprising a casing having a central compartment open at its upper end, a chamber in lower end communicating with the upper end of said central compartment through a stand pipe, a water chamber partly surrounding said central compartment and communicating at its lower end with the lower end of the latter, a purifier chamber communicating with said lower compartment and with the service pipes, a horizontal partition wall in said casing closing the upper end of the water chamber and the purifier chamber, a carbid bucket open at its upper end disposed in said central compartment, and provided between its ends with perforations through which water is admitted, inverted V-shaped troughs disposed in the path of the admitted water to divide and distribute the same to

various parts of said bucket, a cylinder open at its lower end entering said central compartment and receiving said carbide bucket and said stand pipe, a chamber above said cylinder communicating with the lower end of the latter, and a vent communicating with said chamber.

4. An acetylene gas generator comprising a casing having a central compartment open at its upper end, a chamber in lower end communicating with the upper end of said central compartment through a stand pipe, a water chamber partly surrounding said central compartment and communicating at its lower end with the lower end of the latter, a purifier chamber communicating with said lower compartment and with the service pipes, a horizontal partition wall in said casing closing the upper end of the water chamber and the purifier chamber, a carbide bucket open at its upper end disposed in said central compartment, a tapered chamber above said cylinder of larger diameter at its upper than at its lower end, and communicating at its lower end with the lower end of said cylinder, and a vent communicating at its lower end with the lower end of said cylinder, and a vent communicating with said chamber at its upper end.

5. An acetylene gas generator comprising a casing having a central compartment open at its upper end, a chamber in lower end communicating with the upper end of said central compartment through a stand pipe, a water chamber partly surrounding said central compartment and communicating at its lower end with the lower end of the latter, a purifier chamber communicating with said lower compartment and with the service pipes, a horizontal partition wall in said casing closing the upper end of the water chamber and the purifier chamber, and disposed below the upper wall of the casing, the said upper wall of the latter being provided with a central opening of larger area than the said central compartment, a carbide bucket open at its upper end disposed in said central compartment, a cylinder open at its lower end entering said central compartment and receiving said carbide bucket

and said stand pipe, a chamber above said cylinder communicating with the lower end of the latter, and a vent communicating with said chamber, a tapered chamber above said cylinder of larger diameter at its upper than at its lower end, and communicating at its lower end with said cylinder, and a vent communicating with said chamber at its upper end, the upper end of said tapered chamber fitting said central opening in the upper wall of said casing.

6. An acetylene gas generator comprising a casing having a central compartment open at its upper end, a chamber in lower end communicating with the upper end of said central compartment through a stand pipe, a water chamber partly surrounding said central compartment and communicating at its lower end with the lower end of the latter, a purifier chamber communicating with said lower compartment and with the service pipes, a horizontal partition wall in said casing closing the upper end of the water chamber and the purifier chamber, and disposed below the upper wall of the casing, the said upper wall of the latter being provided with a central opening of larger area than the said central compartment, a carbide bucket open at its upper end disposed in said central compartment, a cylinder open at its lower end entering said central compartment and receiving said carbide bucket and said stand pipe, a tapered chamber above said cylinder communicating with the lower end of the latter, and a vent communicating with said chamber, the upper end of said tapered chamber fitting said central opening in the upper wall of said casing, and locking means disposed on said upper wall and adapted to engage said cap to hold said cylinder at the lower limit of its movement.

In testimony whereof I have signed my name in the presence of two subscribing witnesses.
